UNITED STATES PATENT OFFICE.

WILLIAM E. BERTRAM, OF BROOKLYN, NEW YORK, ASSIGNOR TO INTERNATIONAL TYPESetting MACHINE COMPANY, OF NEW YORK, N. Y., A CORPORATION OF NEW YORK.

LINOTYPE-MACHINE.

1,108,829.

Specification of Letters Patent. Patented Aug. 25, 1914.

Application filed November 8, 1912. Serial No. 730 227.

To all whom it may concern:

Be it known that I, WILLIAM E. BERTRAM, a citizen of the United States, residing at Brooklyn, in the county of Kings and State 5 of New York, have invented new and useful Improvements in Linotype-Machines, of which the following is a specification.

My present invention relates to improvements in line casting machines, more especially to those adapted to assemble and cast from matrices bearing a plural number of characters arranged at different levels.

In the operation of such machines, matrices bearing a plurality of characters 15 are assembled and temporarily supported at different levels during assemblage, and in front of the mold during process of casting, by means embodying a rail which supports the matrices at the different levels, succeeding 20 which the rail is then retracted to permit all of the matrices to come to a common level preparatory to the distribution thereof. Heretofore, such rail has been shifted to and from operative position either by power 25 mechanism operating at intervals, or the rail has been withdrawn by contact and springs have been depended on to reset it.

The primary object of the present invention is to provide a rail or support having 30 simple and improved means for operating it with certainty, insuring the correct positioning thereof at all times, and obviating the complication of power mechanism or the uncertainty of springs.

To these and other ends, the invention consists in certain improvements, and combinations and arrangements of parts, all as will 35 be hereinafter more fully described, the novel features being pointed out particularly 40 in the claims at the end of the specification.

In the accompanying drawing:—Figure 1 is a front elevation of the upper portion of the first elevator of a linotype machine constructed in accordance with the present invention, the elevator being shown in its uppermost or matrix-transferring position; Fig. 2 is a perspective view of one of the elevator jaws showing the matrix-supporting rail in position thereon; Fig. 3 represents 45 a transverse section through the upper portion of the first elevator, the mold wheel, and the spout of the metal pot, and showing a line of matrices in casting position before the mold; Fig. 4 represents a horizontal 50 section through one jaw of the first elevator

in a plane immediately above the shiftable matrix-supporting rail.

Similar parts are designated by the same reference characters in the several views.

The present invention is applicable generally to line casting machines of different types, although it is especially adapted to linotype machines of the type using matrices each bearing two or more characters at different levels thereon and intended to be 60 assembled at different levels so as to present the selected characters to the mold. In the present instance, the invention is shown in connection with the first elevator as commonly used on the well known linotype machine, this elevator serving to receive a line 65 of matrices from the assembling point and to support the line before the mold and to afterward convey the line of matrices to the mechanism which serves to transfer them to 70 the distributing mechanism. This elevator designated 1 may be of the usual construction, that shown embodying co-operative jaws 2 and 3 between which the line of 75 matrices is supported, the mold 4 which is carried by the mold wheel 5 being used to 80 cast the linotype or slug from the matrices, of metal injected into the mold through the spout 6 of the metal pot. The matrix keeper 85 7 is provided with ledges to receive the lower lugs on the matrices, the ledges employed being of a number corresponding to the different levels at which the matrices are to be 90 positioned. In the present instance, the construction is adapted to handle matrices which are assembled and supported at two levels and hence two ledges 8 and 9 are provided.

x and *y* designate respectively the matrices positioned at the upper and lower levels. In the present instance, a bar 10 attached to 95 the elevator jaw 2 serves to support the matrices *y* at the lower level.

According to the present invention, a rail 11 is provided to support the matrices *x* which are arranged at the upper level, this 100 rail being capable of an angular motion while moving toward and from the line of matrices and is provided with simple and effective means for actuating it. This rail in the present instance is fitted to operate 105 horizontally in a recess 12 which is formed in the lower portion of the elevator jaw 2; it having a suitable number of lugs 13 which operate in notches 14 in the jaw. In the present construction, two of these lugs 13 are 110

formed with diagonal or inclined ribs 15 which operate in correspondingly inclined guides or grooves 16 in the elevator jaw whereby the rail will be guided to shift diagonally or in an inclined direction with respect to the inner matrix-supporting edge of the rail. Different means may be provided for retracting the rail when the elevator has been raised into a position to transfer the matrices to the intermediate channel 17 from which they are conveyed to the distributing mechanism. In the present instance, a bell-crank lever 18 is provided, this lever being pivoted at 19 on the elevator jaw 2, one arm 20 of the lever operating in a notch or opening 21 formed in a lug 22 on the matrix-supporting rail, while the other arm 23 of the lever which extends in a substantially horizontal direction at the top of the elevator is arranged to engage the lower end of a plunger 24 when the elevator has been fully raised. In order to avoid injury to any of the parts and to also avoid the necessity of fitting the parts with absolute precision, the plunger 24 is held yieldably in operative position by a spring 25, the spring and plunger being supported by the bracket 26. The line of matrices assembled at the different levels is received by the elevator 30 from the channel 27 by a movement of the matrices in a direction from the right and toward the left, as shown in Fig. 4, and owing to the arrangement of the inclined guides for the matrix-supporting rail 11, any friction caused by the incoming matrices on the rail will prevent retraction or displacement of the rail, this being particularly so where the matrices, as frequently happens, are out of shape or mutilated in such a way 40 as to fit tightly in the passageway, the consequent friction or binding tending rather to keep the rail in correct operative position. The matrices α are supported at the upper level by this rail 11 while the matrices γ are supported at the lower level by the bar 10 while the casting operation is taking place. After the cast has been made, the elevator rises in order to transport the matrices to the distributing mechanism, and when the elevator has substantially reached the limit of its upward movement the plunger 24 acting on the bell-crank lever 18 operates to shift the rail 11 in its diagonal path and in a direction away from the matrices, this retraction of the rail releasing the matrices at the upper level and permitting all the matrices in the line to come to a common level. After the matrices from which the cast has 60 been made are removed from the elevator, the latter descends to receive another line of matrices preparatory to the next casting operation, and the present invention provides means for positively restoring and holding the rail 11, by abutting on the fixed delivery

channel 27, in operative position where it will support in the next line of matrices such matrices as have been assembled at the upper level. Such means consists in the present instance of a track 28 which is fastened to any suitable stationary part of the machine and in the path of the adjacent end of the rail 11, this track in the present instance being fastened to the channel 17 and has a beveled surface 29 which co-operates with the end of the rail 11 which projects beyond the corresponding end of the elevator jaw 2 while the rail is in retracted position. Descent of the elevator causes the track 28 to restore the rail positively to operative position.

I claim as my invention:

1. In a linotype machine, in combination with a first elevator to receive a line of matrices, a rail adapted to support the matrices at an upper level, and means to retract the rail in a direction toward but oblique to the direction of motion of the incoming matrices.

2. In a linotype machine, in combination with matrices having more than one character each, a first elevator having a channel adapted to receive such matrices, and a rail mounted in said elevator and means to retract said rail from said channel in a direction toward but oblique to the motion of the incoming matrices.

3. In a linotype machine, the combination of a first elevator, a horizontally movable rail carried thereby for supporting matrices at an upper level, and means for positively locking the rail in operative position to receive the next incoming line of matrices.

4. The combination of an elevator adapted to receive matrices assembled in a line at different levels, a shiftable rail adapted to support matrices at an upper level, means operative by the movement of the elevator for retracting said rail, and means also operative by movement of the elevator for positively restoring the rail to operative position.

5. The combination, in a line casting machine, of an elevator adapted to receive matrices assembled in a line at different levels, a shiftable rail adapted to support matrices at an upper level, a yieldable abutment operative to retract said rail when the elevator reaches a predetermined point in its movement, and positive means for restoring the rail to operative position.

6. The combination of an elevator adapted to receive matrices assembled in a line at different levels, a shiftable rail adapted to support matrices at an upper level, means for retracting said rail preparatory to the removal of the matrices from the elevator, and means operative by the movement of the elevator for positively restoring the rail to operative position.

7. The combination of an elevator adapt-

ed to receive matrices assembled in a line at different levels, a shiftable rail adapted to support matrices at an upper level, means for retracting said rail preparatory to the removal of the matrices from the elevator, and a track operative on said rail to positively restore it to operative position during movement of the elevator.

8. The combination of a member having means for introducing a line of matrices longitudinally from one end thereof, and means for supporting such matrices at different levels embodying a rail guided to

move obliquely toward the direction of motion of the incoming matrices to support the same and movable obliquely and in a direction opposite to the motion of the incoming matrices to release the same.

In testimony whereof I have hereunto set my hand in presence of two subscribing witnesses.

WILLIAM E. BERTRAM.
